CLAIM

An ornamental design for a ball cap with indicia comprising a football skin, as shown and described.

DESCRIPTION

FIG. 1 is a front, right perspective view of the ball cap with indicia;

FIG. 2 is a front elevation view of the ball cap with indicia; FIG. 3 is a left side elevation view of the ball cap with indicia; FIG. 4 is a right side elevation view of the ball cap with indicia; and,

FIG. 5 is a top plan view of the ball cap with indicia.

A characteristic feature of the design resides in the indicia on the front of the cap that comprises a football skin and the texture thereof.

1 Claim, 5 Drawing Sheets
